UNITED STATES PATENT OFFICE

ALFRED WINKLER AND MAX DÜNNEBIER, OF NEUWIED, GERMANY

FEEDING APPARATUS

Application filed May 31, 1930, Serial No. 457,769, and in Germany October 2, 1929.

This invention relates to feeding apparatus and more particularly to that type of apparatus in which the articles—sorted in grades, kinds or sizes—are fed to a chocolate coating 5 or other treating machine or apparatus, and in which the articles are shaken in order to bring them to an upright position while being conveyed on an endless band or the like.

In feeding apparatus of this type it has 10 been heretofore proposed to provide a stationary inclined slide which is interposed between conveyor means associated with a receptacle for the articles and a conveyor band which latter receives the articles from said 15 slide and conveys said articles while the latter are being brought to an upright position by the action of guide rails or the like. In such apparatus the proper feeding of the articles is frequently interrupted by the adhering of 20 the articles to the stationary slide and to each other.

One object of the present invention is to provide an inclined slide having means for moving the same to insure proper feeding of 25 the articles. A further object of this invention is to provide means for automatically shaking or jolting the slide during the feeding operation. A still further object is to provide shaking or jolting means that are 30 automatically controlled in accordance with the speed of the feeding operation and a still further object of the invention is to provide improved means for regulating the amplitude of the shaking movement and the 35 angle of inclination of the slide.

With these objects in view, the invention consists in the novel construction and arrangement of parts hereinafter described, 40 illustrated in the accompanying drawing and particularly pointed out in the appended claims, it being understood that various changes in the form and minor details may be made without departing from the spirit of the invention or sacrificing any of the advantages thereof.

In the drawing the improved feeding mechanism is shown in vertical section.

In the apparatus shown on the drawing, the 45 inclined conveyor band 1 forms the floor or bottom of a receptacle 2 for the articles and

is adapted to convey such articles—which have already been sorted or separated by any suitable or well known means. The articles are thus conveyed over the roller 3 and are delivered on to the inclined plate or slide 4 55 which is preferably arranged at an angle somewhat less steep than the angle of inclination of the stationary slides heretofore employed in apparatus of this type. From the slide 4 the articles are received on the endless 60 conveyor band 5 which is guided over the flat top of the table 6 and upon which the articles are brought to an upright position by means of the guide rails 7 which are moved transversely of the direction of travel of the articles in the well known manner. The circular brush 8 arranged above the roller 3 of the conveyor band 1 operates in the known manner to prevent obstruction at the outlet of the receptacle 2. The conveyor band 5 is operated 70 by the drum 9 while the band 1 and the brush 8 are driven in any suitable or well known manner preferably from the shaft 10 hereinafter referred to.

The slide 4 is carried by pins or trunnions 75 mounted in bosses 11 and in the side frames 13 mounted upon the base 12 of the machine and at the underside thereof the slide 4 carries a rail or flange 14 having a slot 15 for the accommodation of a block pivoted to a rod 80 16 in such manner that the block may be adjusted in the slot 15 and may be clamped at any position therein. The lower end of the rod 16 is adjustably secured to a forked bracket 18, the rod 16 being passed through 85 an eye in the member 18 and being secured thereto by means of nuts 17 so that longitudinal adjustment of the rod 16 is permitted. The forked portion of the member 18 engages over a shaft 19 which carries a toothed shaking wheel 20 which latter is engaged by a pawl 21 carried by the member 18 and vertically adjustable therein by means of a set screw 23 mounted in the arm 22 of the said member 18. It will thus be understood 90 that the shaking movement of the slide 4 about the pivots 11 can be varied by changing the position of the upper end of the rod 16 in the slot 15 or by adjusting the position 95 of the pawl 21 relatively to the forked-por-

tion of the member 18 and the inclination of the slide can also be regulated by adjusting the rod 16 relatively to the member 18 through the medium of the nuts 17.

5 In the arrangement shown, the said shaft 19 is driven by means of a sprocket wheel 24 from a chain 25 operated by a sprocket wheel 26 on the shaft 10.

10 As the feed band 1 is preferably driven by suitable sprocket or like means from the said shaft 10, the speed of delivery of the articles to the slide 4, and the shaking movement of the latter maintain their proper relation and the shaft 10 may be driven at any 15 desired speed to suit the circumstances and conditions under which the operation is taking place.

10 It will be understood that the number of articles fed to the slide 4 depends directly upon the speed of the conveyor band 1, and it is therefore important that the shaking or jolting motion imparted to the slide 4 be so controlled that the articles are caused to travel over the slide 4 with greater speed 25 when a greater number of articles are fed to the slide by the conveyor 1, and this regulation of the speed of the conveyor 1 in proportion to the jolting or shaking of the slide 4 is an important feature of the present invention.

20 Although the drawing and the above specification disclose the best mode in which we have contemplated embodying our invention, 35 we desire to be in no way limited to the details of such disclosure, for in the further practical application of our invention many changes in form and construction may be made as circumstances require or experience 40 suggests without departing from the spirit of the invention within the scope of the appended claims.

45 What we claim is:

1. Apparatus for supplying articles in an 45 upright position having feed mechanism of the character described, comprising endless bands for conveying the articles, an inclined slide interposed between the bands, means for shaking the slide and means for adjusting the amplitude of the shaking movement.

50 2. Apparatus for the supply of articles in an upright position having feed mechanism of the character described comprising an endless conveyor band for supplying the articles, an inclined slide receiving the articles from said band, means for jolting the slide, and means for varying the amplitude of the jolting movement imparted to the slide.

55 3. Apparatus for the supply of articles in an upright position having feed mechanism of the character described comprising an endless conveyor band for supplying the articles, an inclined slide receiving the articles from said band, means for jolting the slide,

and means for varying the angle of inclination of the jolting slide.

In testimony whereof we have signed our names to this specification.

ALFRED WINKLER.
MAX DUNNEBIER.
